UNITED STATES PATENT OFFICE.

THEODORE A. ROHRMAN, OF PHILADELPHIA, PENNSYLVANIA.

HAMMOCK-SUPPORTING STRUCTURE.

SPECIFICATION forming part of Letters Patent No. 443,544, dated December 30, 1890.

Application filed March 10, 1890. Serial No. 343,306. (No model.)

To all whom it may concern:

Be it known that I, THEODORE A. ROHRMAN, a citizen of the United States, and a resident of Philadelphia, Pennsylvania, have invented 55 certain Improvements in Hammock-Supporting Structures, of which the following is a specification.

The object of my invention is to construct a portable hammock - support which when 10 extended will provide a strong and rigidly-braced frame-work, but which can be readily folded up into compact form for transportation or storage. This object I attain in the manner hereinafter set forth, reference being 15 had to the accompanying drawings, in which—

Figure 1 is a perspective view of my improved hammock-support, showing the same extended in position for use. Fig. 2 is a perspective view of the same in its folded condition. Fig. 20 3 is an enlarged sectional view of a locking device forming part of the structure. Fig. 4 is a perspective view of part of said device, and Fig. 5 is a sectional view of a hinge-joint of one of the braces.

25 The supporting structure comprises four posts A, constituting opposite pairs of posts, one at the head and the other at the foot of the hammock, and to each of these pairs of posts is pivoted a yoke B, having at the outer 30 end a hook a, one of these hooks receiving the ring at one end of the hammock cord or rope, while the other receives the ring at the opposite end of said rope. When the yokes are extended and the hammock is swung between 35 the hooks a, said hooks are in a higher plane than the pivots b of the yoke; hence the strain upon the hammock tends to pull the yokes inward, or toward each other, this movement, however, being resisted by contact of arms d 40 upon the yokes with stops f upon the posts A of the frame.

The bracing structure for each pair of posts consists of an upper bracing-frame D and a lower bracing-frame F, each of these frames 45 being hung to a transverse brace-rod g, connecting the posts of the pair so that each of the bracing-frames D and F is free to swing on its rod, the rod carrying the upper frame D being above the rod which carries the lower 50 frame F. The opposite pairs of posts are also

connected by longitudinal side braces J, each composed of two bars, which are hung to the rods g at the ends, and are pivoted together in the center by means of a transverse rod w, the hinge-joint at the center of each brace J 55 being such that it can yield upwardly, but cannot be depressed below a horizontal line. (See Fig. 5.)

The opposite bracing-frames D unite at their inner ends in the plates h, which are connected 60 by means of a pivot-pin i, as shown in Fig. 3, and each of these plates h has an outwardly-projecting rod m, which serves as a guide for a block p, pivoted to the inner end of the corresponding bracing-frame F. 65

When the supporting structure is set up in position for use, the bracing-frames D D and J J occupy a substantially horizontal position, while the frames F are inclined upward from their pivot-rods to the sliding blocks p, the latter being at the inner ends of the guide-rods m, and being locked in this position by means of a turn-buckle s, which engages with headed pins t on the sliding blocks p, as shown in Fig. 3. By this means a firm and rigid bracing 70 of the opposite pairs of posts A is effected, yet upon releasing the pins t from the control of the turn-buckle either set of braces may be readily turned upward, so as to permit the opposite pairs of posts to be brought closely 75 together, as shown in Fig. 2, the blocks p of the lower braces sliding outward on the guide-rods m as the braces are thus turned upward.

In order to provide an additional support for the structure, I in some cases provide a 85 pendent leg G, having a suitable foot w', carrying the rod w, this leg being forked at the upper end and hung to the pivot-rod i, which connects the braces D D. As the inner ends of the braces D rise, therefore, there will be a 90 simultaneous upward movement of the meeting ends of the side braces J, movement being imparted thereto through the medium of the leg G and rod w. The side braces J may, however, be disconnected from the other parts of 95 the bracing structure, if desired.

My invention provides a hammock-supporting structure which when folded occupies but a small space, and can be readily stored away within the house, or can be conveniently trans- 100

ported from place to place and readily set up in any desired position.

Having thus described my invention, I claim and desire to secure by Letters Patent—

1. The combination of the opposite pairs of posts with their hammock-supporting yokes, and a bracing structure comprising upper and lower bracing-frames pivoted to the posts, the upper frames being pivoted together where they meet, and the lower bracing-frames having at their inner ends sliding blocks guided on the upper frames, substantially as specified.
2. The combination of the opposite pairs of posts and their hammock-supporting yokes with the bracing structure, comprising the upper bracing-frames pivoted to the posts and pivoted together at their meeting ends, the lower bracing-frames pivoted to the posts and having at their inner ends sliding blocks guided on the upper frames, and a pivoted locking-lever for said blocks, substantially as specified.
3. The combination of the opposite pairs of posts and their connecting-braces with the hammock-supporting yokes pivoted to said

pairs of posts and having arms for contact with stops on the posts to limit the movement of the yokes, substantially as specified.

4. The combination of the opposite pairs of posts and their hammock-supporting yokes with upper, lower, and side braces pivoted to said opposite pairs of posts, the upper and side braces being pivoted together at their meeting ends and the lower braces having sliding blocks guided on the upper braces, substantially as specified.

5. The combination of the opposite pairs of posts, the pivoted side braces connecting the same, the transverse rod connecting the meeting ends of the opposite side braces, intermediate pivoted braces, and a pivoted pendent leg carried thereby and carrying said transverse rod, substantially as specified.

In testimony whereof I have signed my name to this specification in the presence of two subscribing witnesses.

THEO. A. ROHRMAN.
